UNITED STATES PATENT OFFICE.

JAMES B. KIRBY, OF CLEVELAND, OHIO.

WASHING-MACHINE.

1,277,604.

Specification of Letters Patent.

Patented Sept. 3, 1918.

Application filed July 19, 1915. Serial No. 40,555.

To all whom it may concern:

Be it known that I, JAMES B. KIRBY, a citizen of the United States, residing at Cleveland, in the county of Cuyahoga and State of Ohio, have invented a certain new and useful Improvement in Washing-Machines, of which the following is a full, clear, and exact description, reference being had to the accompanying drawings.

10 This invention relates to washing machines and has for its general object the provision of new, improved, and simplified mechanism for forcing cleansing liquids through the fabrics, and afterward removing the liquids therefrom. In the performance of my said invention I preferably employ a fabric-receiving tub or container of perforated or foraminous material movably supported within a liquid-containing casing 15 in such a manner as to support the fabrics for washing purposes, and after washing to be elevated above the liquid surface and rotated at a high speed for removing adherent liquid from the fabrics. Subsidiary 20 objects of my invention are the provision of new and improved means for operating the washing devices; the provision of means whereby clothing or fabrics deposited within the tub or container may be automatically 25 distributed therearound so as to be substantially balanced for wringing purposes; the provision of new and improved means for disposing of the washing devices during the wringing operation; the provision of 30 new and improved means for varying the relative position between the washing devices and the tub or container so that all portions of the fabrics may be efficiently 35 cleansed; the provision of a construction 40 wherein the washing operation shall be independent of the amount of clothing or fabrics operated upon at one time and in which the mechanism cannot be stalled or broken by an excess; the provision of an 45 operating mechanism wherein the same power which effects the washing motion shall also aid in elevating the container; the provision of a new and improved construction.

of tub or container; the provision of new and improved expedients for draining the 50 casing; while further objects and advantages will become apparent as the description proceeds.

Generally speaking my invention may be defined as consisting of the combinations and 55 constructions recited in the claims hereto annexed and illustrated in one embodiment in the drawings accompanying and forming a part of this application wherein: Figure 1 is a side elevational view of my improved 60 washing machine, certain parts being partly broken away, and the housing for the mechanism omitted, the washing devices being at the upper limit of their stroke; Fig. 2 is a view similar to Fig. 1 showing the wash- 65 ing devices at the lower limit of their stroke; Fig. 3 is a vertical central sectional view of my improved washing machine corresponding substantially to the line 3—3 of Fig. 8; Fig. 4 is a view similar to Fig. 1 70 showing the tub in elevated or wringing position and the washing devices completely displaced; Fig. 5 is a front elevational view of my improved washing machine showing the same inclined for draining and omitting 75 the housings; Fig. 6 is a top plan view of my improved washing machine, the cover being omitted; Figs. 7 and 8 are cross sectional views on the lines 7—7 and 8—8, respectively, of Fig. 1; Figs. 9 and 10 represent side and front elevations, respectively, 80 of the complete machine including the housings; Fig. 11 is a detail view drawn to enlarged scale showing the pounder-operating devices in their extreme positions of operation; Fig. 12 is a detail view illustrating 85 one mode of connecting the pounder arm to its operating rod; Fig. 13 is a detail view showing the shape and arrangement of the pedals; Fig. 14 is a perspective view of the 90 anti-splashing plate; Fig. 15 is a perspective view of a portion of the operating mechanism; and Fig. 16 is a detail view of the casing-tilting device.

Describing the parts by reference characters, 1 represents the outer casing or recep-

tacle of my improved machine, the same being preferably of metal and having a cylindrical side wall and a flat bottom wall 2, the whole being supported at a convenient height by a suitable framework and having its axis substantially vertical. This framework preferably consists of three vertical legs 3, 4, 5, extending from the floor to the top of the casing 1. The legs 3 and 4 are preferably connected by two horizontal bars 6 and 7, respectively, the former serving as a support for the casing and the latter being located near the lower ends of the legs and forming a support for one end 15 of the operating mechanism. Integral with these bars and projecting horizontally rearwardly therefrom are the U-shaped frames 8 and 9, respectively, whose rearward ends encircle and are secured to the leg 5, this 20 rearward leg being preferably of a hollow channel bar, as shown in Figs. 7 and 8, for a purpose to be hereafter disclosed.

Carried by the frame 8 is the vertical bearing-sleeve 10 which projects through the bottom wall 2 of the casing to a considerable distance above the bottom thereof as shown in Fig. 3, leakage around the same being prevented in any suitable manner as by packing. Slidably and rotatably journaled inside said sleeve is the vertical shaft 11, having at its lower end a suitable anti-friction bearing 12, here shown as a rounded cap formed with an enlarged base, and having rigidly secured to its upper end the vertical sleeve 13 which freely surrounds the upper end of the sleeve 10. Carried by the sleeve 13 is the tub or container, whose preferred construction is as follows:

The bottom of the tub is formed from a 40 flat sheet of copper or other suitable metal by spinning or stamping the same to produce an abrupt inwardly facing annular shoulder 15 having at its outer side the upwardly and outwardly inclined portion 16 45 terminated by the upstanding peripheral flange 17, and having upon its interior the upwardly and inwardly inclined portion 18 terminating in an upwardly turned lip 19 surrounding the central aperture. Above 50 this bottom I place a second frusto-conical plate 20 of greater slope than the portion 18 of the bottom plate, having a central aperture defined by a downturned lip 21 registering with the lip 19 and having its outer 55 edge abutting against the shoulder 15. Through the apertures defined by the lips 19 and 21 I pass a short tube 22 and spin it or upset it so as to secure the two bottom members rigidly together, afterward preferably sweating or brazing the same with copper or spelter both at the center joints and at the shoulder 15 so as to form a hermetically sealed air chamber. Also this construction produces a kind of truss which

affords great stiffness to the tub even though 65 comparatively thin metal be employed. The tub bottom may be secured to the sleeve 13 in any suitable manner as by the jam nuts 24—24 threaded above and below the same.

Inside the flange 17 I secure a vertical 70 cylindrical perforated wall 25 and to the top of this wall I secure a coping 26, preferably having a peripheral flange 27 embracing the wall 25 and having its main part deflected upwardly and inwardly as shown 75 in Fig. 3 to a rolled rim 28. The plate 20 in conveniently cut from the center of the blank which forms this coping. The sleeve 13 is preferably secured to the shaft 11 by some simple and easily detachable means 80 such as the nut 29. The outer portion 16 of the bottom is preferably perforated, as shown.

Rotatably journaled upon the exterior of the sleeve 10 is a friction wheel 30 to which 85 is rigidly secured the pinion 31 which meshes with the gear 32 journaled to the stud 32 carried by the bar 6, and operatively connected to the gear 32 is the eccentric pin 33 by means of which motion is 90 transmitted to the pounder mechanism. In the present embodiment the pin 33 is carried by the face of a pinion 34 whose hub is rigidly connected to the gear 32, this construction being adopted for the purpose of 95 transmitting motion to the tub or container in a manner to be hereafter described, although it will be obvious that other constructions could be employed.

Secured to the upper side of the bar 7 is 100 a horizontal pivoting member 36 upon which are hinged three sleeves 37, 38, and 39. Projecting from the sleeve 37 is an arm 40 whose free end carries a horizontal pin 41 which works between the jaws 42—42 projecting perpendicularly from the vertically reciprocable rod 43. This rod is located inside the hollow leg 5, heretofore mentioned, and is guided in its reciprocation by suitable anti-friction members such as the rollers 44. 105 Secured to the upper end of this rod is the horizontal arm 46 whose free end is normally disposed over the center of the tub and supports the pounders, here shown as 110 hollow downwardly opening bells or cones 47—47. Preferably some expedient is employed for permitting these pounders to be moved out of the way during the filling and emptying of the tub, and I have here shown two expedients for this purpose, of which either one or both may be used in practice. I have illustrated the end of the arm 46 as 115 formed with a hollow, vertically-bored, sleeve 50, swiveled upon the exterior of a bearing 51 securely clamped to the end of the rod 43. The sleeve is secured against endwise movement by means of suitable washers 52—52, and is impositively held

against angular movement by any suitable catch, such as the ball 53 located in the radial recess 54 and impelled by a spring 55 into engagement with suitable recesses 56 formed in the bearing 51. By this means the beaters or pounders can either be held in the operating position shown in Figs. 1, 2 and 6, or can be swung out of the way as shown by the dotted lines in Fig. 6.

10 As a second expedient for permitting the cones to be moved out of obstructing position, I have shown their carrying arms 58-58 as secured to a semi-circular yoke 59, said yoke being pivoted to a block 60 carried by the arm 46 by means of a horizontal pin 61, thus permitting them to be turned either downwardly as shown in Figs. 1, 2 and 6, or upwardly as shown in Fig. 4. This can be used either in connection with the pivoted 15 arm shown or with a fixed arm.

Adjacent to the rod 43 the arm 46 is first made vertical for a distance as shown at 62, this distance being not less than the amplitude of vibratory movement of the 20 pounders, and a cover 63 is provided for the casing, the rearward portion of said cover having an aperture 64 for the passage of this part of the arm.

The sleeve 38 carries a rigid arm 68 which 25 extends beneath a transverse finger 69 extending laterally from the side of the arm 40; the upper side of the sleeve 38 carries a boss 70 to which is pivoted the operating lever 71 whose upper end is formed with a cup 72 receiving the ball 33. The lower side of the lever 68 is formed with a depending branch 73 to which is attached the tension spring 74, whose opposite end is secured to the post 75 carried by the frame 9.

30 Projecting from the sleeve 38 is the arm 79 whose free end carries a laterally extending gudgeon 80 on which is journaled the roller 81. From the lower side of the arm 79 extends the pedal 82 ending in the foot plate 83. Pivoted at the rearward end of the 35 frame 9 upon a transverse horizontal axis is the arm 85 whose forward end terminates in a curved, upwardly-facing shoe 86 receiving the bearing cap 12, while the lower part of said shoe constitutes a curved track 87 which rests upon the roller 81. From the side of the shoe a bracket 88 projects carrying the pivoted roller 89 and the spring 90, the opposite end of said spring being secured to the end of the pin 41. Journaled in the 40 bars 6, 7 is an upright rock shaft 92 to which is secured the arm 93 of the shaft 94 on which stands the motor 95 having a face plate 96 contacting with the friction wheel 45 50 55 moved to one side against the tension of the 95 spring and stop the machine. The vertical position of the shelf is fixed by the set screw 100, which permits the motor to be raised or lowered and the normal speed of the machine varied at will. 70

Upon the rotation of the plate 30 by the motor, the lever 71 will be rocked and with it the arm 68 which, upon its upward movement, will carry the arm 40 through the agency of the finger 69. Arrived at its upper point the tendency of the arm 68 is to leave the finger 69, and such will in fact occur in case the downward movement of the cones be prevented for any reason, but normally the cones are brought back to their 80 lowest position by means of the spring 90, the point 88 being so located as always to lie beneath a straight line joining the points 41 and 36 when the tub is in depressed position. The varying positions assumed by the parts are illustrated most clearly in Figs. 1, 2 and 11, particularly in the last named figure in which the arc $a-a$ is drawn around the point 88 as a center so as to illustrate the nature and extent of the spring action. The strength of the spring 90 is preferably such as to cause the finger 69 to follow the arm 68 closely upon its downward stroke, under ordinary condition of load, although this may be influenced by the amount and density of the fabrics in the tub. In fact if any unusual obstruction intervenes, either a solid object, or a too large mass of clothing, or even the operator's arm, the descent of the cones will be arrested but without damage to the machinery or to the intervening object. 105

During the normal washing operation, as just explained, the arms 79 and 85 have no function, excepting that the shoe 86 may and preferably does serve, at least to some extent, to support the weight of the tub, and that the bracket 88 forms one point of attachment for the spring 90. However, when it is desired to elevate the tub out of the water for draining and wringing purposes, the pedal 82 is depressed which raises the arm 79 and causes the roller 81 to move along the lower edge of the shoe, elevating the latter to the position shown in Fig. 4 and carrying with it the shaft 11. At the same time the roller 89 comes into engagement with the lower edge of the arm 40 and raises this arm also, so as to move the pounders out of obstructing position; and, since the length of the arm 40 is greater than that of the arm 79, the distance moved by the pounders is proportionately greater than that moved by the tub so that the washing devices are lifted entirely out of the casing where they can either be left as illustrated in Fig. 4 or swung to one side as illustrated in dotted lines in Fig. 6. The effect of elevating the 110

shoe 86 is not only to elevate the tub while maintaining an efficient anti-friction bearing for the lower end of the shaft, but also to relieve the tension upon the spring 90. If the lower point of attachment of the spring 90 were not elevated at the same time as the tub, it would be nearly impossible to elevate the tub at all since the operation would be opposed both by the dead weight of the tub and fabrics and by the entire pressure of the cones caused by the great elongation of the spring. With the construction illustrated the effect of the spring 90 is to facilitate the elevation of the tub, since the distance between its ends is less when the parts are in the position shown in Fig. 4 than they are when the parts are in the positions shown in Figs. 1 and 2; in other words the potential energy of the system is less with the levers raised than with the levers lowered, and in the preferred embodiment this is so far true that the weight of the tub is nearly balanced. Also the shape of the trackway 87 is so adjusted that the beginning of the tub movement is facilitated; and the shape of the lower edge of the arm 40 is so adjusted that when the tub is fully raised the arm 85 is nearly perpendicular thereto. In order to lock the tub in elevated position I have provided a locking pedal or catch consisting of a curved lever 103 pivoted to the side of the lever 79 at the point 104 and having at its free end the toe plate 105. Normally this locking lever is maintained in elevated position by means of a tension spring 106 as shown in Figs. 2, 4 and 8, while its upper edge is formed with a shoulder 107 adapted to engage the edge of the bar 7 when the main pedal is depressed.

In order to distribute the clothes evenly about the tub during the washing operation so that there shall be no undue vibration while wringing, I provide a plurality of pounders symmetrically disposed as regards the center of the tub, in the present instance two in number, and in addition I effect a relative rotary movement between said tub and pounders so that all parts of the fabrics may be acted upon and the fabrics uniformly distributed. In the present embodiment the tub is rotated at low speed during the washing operation, such rotation being effected by the gear 110 meshing with the pinion 34 and having a driving connection with the shaft 11 through the agency of the pin 111 and keyway 112. The friction wheel 30 is normally maintained at a fixed height by having its hub rest upon a collar 113 carried by the sleeve 10, while the gear 110 is maintained in place by means of a flat circular plate 114 secured to its upper face and resting upon a flange carried by the same collar. The exterior of the plate 114 is slightly beveled and lies inside of a similarly beveled annular rib 115 formed on the lower face of the friction wheel 30.

The relation of parts is such that upon the elevation of the shaft 11 the flange of the cap 12 first comes in engagement with the hub 116 of the wheel 110 and lifts this wheel out of mesh with the pinion 34, at the same time bringing the plate 114 into engagement with the rib 115 so as to establish driving contact. Continued vertical movement of the shaft moves the friction wheel 30 upwardly along the friction disk 96 and increases the speed of rotation to the extent necessary for complete wringing. Preferably the shoulder 107 of the locking pedal is so located as to support the tub with driving connection established between the wheels 30 and 110 but without any material elevation of the wheel 30. The starting of the tub from a condition of rest to a condition of even moderate rotation absorbs so much energy as frequently to require a considerable amount of time, during which the fabrics will be draining into the casing and the operator can be doing other things. This slow picking-up of speed is permitted by the friction clutch 114-115 without overloading the motor. As soon as the rotation of the tub has reached this degree the clothes will have been found quite thoroughly drained, and the tub will thereafter rapidly pick up any speed desired upon a further depression of the pedal 82. Also this arrangement requires the presence of the operator during the time that high speed is maintained since the release of the pedal 82 immediately permits the speed to decrease down to the point limited by the locking pedal 103. The curvature of the arm 40 permits a large range of movement of the lever 85 at this point without moving the lever 40.

The distribution of the clothes by the operation of the pounders will be found to be remarkably uniform so that no dangerous vibration will ordinarily be experienced even at a speed of a thousand revolutions per minute. However, with a washing machine of the construction here shown I have found that the vibration is less in case the machine be freely supported upon casters than in case it be non-movably attached, this apparently being due to the fact that the upper part of the machine where the rotation takes place is heavier than the lower part so that a considerable movement of the lower part is unimportant, but any material movement of the upper part is obnoxious.

The container and framework are located upon opposite sides of the liquid-position, which constitutes the center of mass of the stationary parts. The container and framework both being lighter than the casing and liquid, the effect of an unbalanced weight in

the container is to vibrate the framework in case the framework is yieldingly supported as by casters or rollers, the inertia of the casing and liquid serving to reduce the vibration and consequent splashing to a minimum. However if the framework be rigidly secured as by omitting the casters, so that a vibration-outlet is denied, the casing and liquid will generally be violently agitated.

10 It will be seen that during the washing operation the only function of the motor is to raise the arm 40 against the action of the spring 90. The purpose of the spring 74 is to store up energy from the motor during 15 the descent of the arm 40 so as to aid the next elevation of the pounders. This saves power and permits a smaller motor to be used. It also serves to stop the machine with the pounders raised in every instance, 20 thus leaving the clothes free. It also holds the levers and gears in the same position at all times during wringing and facilitates the remeshing of the same when the container is lowered.

25 In the casing beneath the tub or container I preferably place an anti-splashing plate adapted to ride upon the surface of the water and prevent its being splashed against the revolving tub by the vibration of the 30 casing or being sucked up as a whirlpool by the air-motion. I have shown a light wooden lattice 121 adapted to be depressed when the tub is lowered and to float on the liquid surface when the tub is raised, though 35 other materials could be used. This lattice is of a size to fit closely into the casing and has a central aperture 122 for the sleeve 10.

For the purpose of draining the casing I have shown a suitable outlet cock 125 located 40 at the side of the machine opposite to the motor, in combination with a suitable elevating device attached to the leg opposite thereto. In the present embodiment said elevating device comprises a slotted plate 45 126 slidably secured upon a rivet 127 carried by one of the legs and having its upper end pivoted at 128 to a rocking plate 129 pivoted at 130. This plate is preferably formed with oppositely projecting arms 131 and 132 whereby it may be operated, and is so constructed and arranged that when the three 50 pivots are brought substantially into line that leg will be elevated one or two inches above the floor and will be held in that position by means of a finger 133 on the plate engaging the side of the plate 126.

The operating mechanism is preferably inclosed in some kind of a housing, which in the present case consists of a U-shaped 55 member 140 formed of thin sheet metal and secured to the outer faces of the frames 8 and 9, in combination with a curved, somewhat conical portion 141 secured to the forward face of the bars 6, 7, and inclosing the

gears and levers. The sides of the member 65 140 are preferably cut away as shown at 142 to give access to the friction wheel.

While I have described my invention in detail and pointed out at length the constructions and arrangements which my experiments now indicate to be most desirable, I do not limit myself to such details or arrangements except as the same may be positively included in the claims hereto annexed or may be rendered necessary by the prior 75 state of the art.

Having thus described my invention, what I claim is:—

1. In a washing machine, a casing, a perforated container in said casing for receiving the articles to be washed, means for raising and lowering said container, washing devices adapted to act upon such articles while said container is in the lower part of said casing, and means operative upon the raising 80 and lowering of said container for elevating said devices out of said container.

2. In a washing machine, a casing, a perforated container in said casing for receiving the articles to be washed, means for 90 raising and lowering said container, washing devices supported above said container, and means operative upon the raising and lowering of said container for raising and lowering said washing devices through a distance greater than the movement of said container.

3. In a washing machine, a container for the articles to be washed, pounders in said container arranged for simultaneous vertical movement, a single operating lever connected to all of said pounders, power driven means for moving said lever in a direction to raise said pounders and means including a spring for moving said lever in the opposite direction to depress said pounders.

4. In a washing machine, a container for the articles to be washed, pounders in said container arranged for vertical movement, spring means for depressing said pounders, 110 a motor and a spring both adapted alternately to elevate said pounders and to become disconnected therefrom, and means connecting said motor to said spring when the same are disconnected from said pounders whereby the energy of said motor may be imparted to said spring prior to the subsequent connection of said pounders thereto.

5. In a washing machine, a casing, a vertically movable container therein for receiving the articles to be washed, a vertically movable part supporting said container, agitating devices arranged in said container, actuating means operatively connected to said devices, a power source, mechanism operative while said container is in lowered position for connecting said source to said actuating means, mechanism for producing

a rotation of said container simultaneously with such actuation, means for elevating said container, and means operative simultaneously with such elevation for disconnecting

5 said power source from said actuating means and connecting it solely to said movable part in rotating relation.

6. In a washing machine, a container for the articles to be washed, pounders in said 10 container arranged for vertical movement, spring means for depressing said pounders, a power driven, reciprocable device adapted to elevate said pounders when moving in one direction and disconnected therefrom when 15 moving in the opposite direction, and a spring connected to said device and opposing the last-named movement thereof.

7. In a washing machine, a casing, a vertically movable perforated container there- 20 in for receiving the articles to be washed, a vertically movable part supporting said container, pounders arranged for vertical movement in said container, mechanism for reciprocating said pounders, means for raising 25 and lowering said container, a power source, and means operative upon elevating said container to disconnect said power source from said reciprocating mechanism and connected to said supporting part, and also upon 30 lowering said container to disconnect it from said supporting part and connect it to said reciprocating mechanism.

8. In a washing machine, a casing, a container in said casing for receiving the arti- 35 cles to be washed, means for raising and lowering said container, pounders arranged for vertical movement in said container, mechanism for raising said pounders, and spring means for depressing said pounders, said 40 spring means being attached to said container-raising means.

9. In a washing machine, a casing, a vertically movable container therein for receiving the articles to be washed, a vertically 45 movable part supporting said container, agitating devices arranged for vertical movement in said container, a vertically movable part operatively connected to said devices, a spring connecting said parts and tending to 50 depress said agitating devices, mechanism adapted to elevate said last named part intermittently against the tension of said spring and to permit its depression by said spring during the intervals between such 55 elevations, and means for elevating said parts simultaneously so as to raise said container and agitating devices together.

10. In a washing machine, a casing, a cylindrical container located therein with its 60 axis substantially vertical, means for raising and lowering said container, washing devices adapted to coöperate with said container while in depressed position to wash materials contained therein, means for rotating said container at high speed when the

same has been moved to elevated position, and means operative upon the elevation of said container for moving said devices out of coöperating relation therewith.

11. In a washing machine, a casing, a cylindrical container located therein with its axis substantially vertical, a shaft carried thereby, means for raising and lowering said container, a driving wheel concentric with said shaft, gearing connecting said driving 70 wheel with said shaft while the container is in depressed position and adapted to rotate the same at a slower speed than said wheel, and means operative upon the elevation of said container for disconnecting said gear- 75 ing and connecting said wheel directly to said shaft.

12. In a washing machine, a casing, a cylindrical container located therein with its axis substantially vertical, a shaft connected 80 to said container, means for raising and lowering said container, a driving wheel concentric with said shaft, a constantly rotating driving element operatively engaging said wheel, gearing connecting said driving 85 wheel with said shaft while the same is in depressed position and adapted to rotate the container at a slower speed than said wheel, means operative upon the elevation of said container for disconnecting said gearing and 90 connecting said wheel directly to said shaft, and means operative after such connection for increasing the speed of said driving wheel relatively to said driving element.

13. In a washing machine, a casing, hav- 100 ing a vertical bearing in its bottom wall, a shaft slideable and rotatable in said bearing, a cylindrical container secured to the upper end of said shaft with its axis substantially vertical, means for raising and lowering said shaft, a friction wheel concentric with said container, a constantly rotating friction disk parallel to said shaft and engaging said wheel, gearing connecting said friction wheel with said shaft while the same is in 105 depressed position and adapted to rotate the same at a slower speed than said wheel, means operative upon the elevation of said shaft for disconnecting said gearing and connecting said friction wheel directly to 110 said shaft, and means for elevating said shaft and wheel simultaneously after such connection, whereby said container is lifted higher out of the liquid in said casing, and its speed increased relatively to said friction 115 wheel.

14. In a washing machine, a casing, a cylindrical container located therein with its axis substantially vertical and movable be- 125 tween upper and lower positions in said container, washing devices adapted to coöperate with said container, means operative during the time that said container is in its lower position for actuating said washing devices, a power source operatively connected to said 130

means, and mechanism whereby said container can be raised to its upper position and said power source disconnected from said washing devices and connected in driving relation to said container without interrupting the operation of the machine.

15. In a washing machine, a casing, a cylindrical container located therein with its axis substantially vertical and movable to and between upper and lower positions therein, washing devices adapted to operate inside of said container, when the same is in its lower position, power driven operating mechanism connected to said devices while said container is in lower position, and a single lever operatively connected to said container, washing devices, and operating mechanism and adapted to elevate said container, to elevate said washing devices out of said container, to disconnect said operating mechanism from said devices, to connect said operating mechanism in driving relation to said container, and to vary the speed of rotation of said container.
- 20 16. In a washing machine, a casing, a cylindrical container located therein with its axis substantially vertical and movable to and between upper and lower positions therein, power driven means for washing articles in said container when the same is in its lower position, and a single lever operatively connected to said container, washing devices and operating mechanism and adapted, when moved in one direction, to elevate said container, to disconnect said operating mechanism from said washing devices, to connect said operating mechanism in driving relation to said container, and to increase gradually the speed of rotation of said container.

- 25 17. In a washing machine, a casing, a cylindrical container located therein with its axis substantially vertical and movable to and between upper and lower positions in said casing, a shaft connected to said container, a drive wheel, means for rotating said drive wheel continuously, reduction gearing adapted to be connected between said drive wheel and said shaft while the container is in its lower position, means for clutching said driving wheel to said shaft in high speed driving relation while the container in its upper position, and a single pedal adapted when depressed to elevate said container and disconnect said reduction gearing and to connect said driving wheel directly to said shaft.

- 30 18. In a washing machine, a casing, a cylindrical container located therein with its axis substantially vertical and movable to and between upper and lower positions in said casing, a shaft connected to said container, a drive wheel, means for rotating said drive wheel continuously, reduction gearing for connecting said drive wheel to

said shaft while the container is in its lower position, means for clutching said driving wheel to said shaft while the container is in its upper position in said casing, and a single lever adapted to elevate said container 70 and to disconnect said gearing and to clutch said driving wheel to said shaft and said lever being adapted when moved farther in the same direction to increase the speed of rotation of said container relatively to said 75 wheel.

19. In a washing machine, a casing, a cylindrical container located therein with its axis substantially vertical and movable to and between upper and lower positions 80 in said casing, a drive wheel, means for rotating said drive wheel continuously, means for connecting said drive wheel to said container in one operating relation while the same is in its lower position, means for connecting said driving wheel to said container in another operating relation while the same is in its upper position in said casing, and a single lever adapted to elevate said container and effect such change in relation, 85 and a catch adapted to secure said lever at the point occupied when said driving wheel is attached to said container.

20. In a washing machine, a casing, a cylindrical container located therein with 95 its axis substantially vertical and movable to and between upper and lower positions in said container, a driving element, means for rotating said element at a continuous speed, washing devices adapted to be driven by 100 said element when said container is in its lowest position, means for elevating said container and simultaneously disconnecting said driving element from said washing devices, locking means for securing said container when so elevated, and friction means 105 operative upon such elevation for connecting said driving element in high speed driving relation with said container.

21. In a washing machine, a casing, having a vertical bearing in its bottom wall, a shaft slidably and rotatably journaled therein, a cylindrical container secured to the upper end of said shaft, a friction clutch having one member rotatable with said shaft, a 115 driving wheel connected to the other clutch member, means for rotating said wheel, washing devices adapted to be driven by said wheel when said container is in its lowest position, a support for said casing, 120 and a pedal carried by said support and adapted when depressed to elevate said shaft and container, such elevation also serving to disconnect said washing devices and to bring the members of said friction clutch 125 into engagement.

22. In a washing machine, a casing, a cylindrical container located therein with its axis substantially vertical and movable to and between upper and lower positions in 130

said casing, vertically reciprocable pounders adapted to operate upon materials in said tub while the same is in depressed position and to be elevated thereabove when the same is in its upper position, and means including a single spring operating to force said pounders downwardly when said container is depressed and to hold said pounders in their upward position when said container 10 is elevated.

23. In a washing machine, a casing, a cylindrical container located therein with its axis substantially vertical and movable to and between upper and lower positions in 15 said casing, vertically reciprocable pounders adapted to operate upon materials in said tub while the same is in depressed position and to be elevated thereabove when the same is in its upper position, and means including 20 a single spring operating to force said pounders downwardly when said container is depressed and to help raise the container to its elevated position.

24. In a washing machine, a casing adapted to hold cleansing liquid in its lower part, 25 a perforated container located therein with its axis substantially vertical and adapted to receive articles to be washed, means for raising and lowering said container, where- 30 by it may either be elevated above the liquid level or brought into contact with the liquid for washing the articles therein, means oper- 35 ate while said container is elevated for rotating it rapidly whereby said articles may be dried, and anti-splashing means adapted to float upon the liquid in said casing during the time that said container is elevated and to be submerged when said container is depressed.

40 25. In a washing machine, a casing, a cylindrical container located therein with its axis substantially vertical and movable to and between upper and lower positions in 45 said container, a rotatable driving element, means operatively connected to said element and adapted to wash articles in said container when the same is in lowered position, and means for disconnecting said driving element from said washing means and for 50 connecting it to said container for rotating the same at high speed when the same is in elevated position.

26. In a washing machine, a casing adapted to hold cleansing liquid in its lower 55 part, said casing having a vertical bearing in its bottom wall, a support for said casing, a shaft slidably and rotatably mounted in said bearing, a cylindrical container secured to the upper end of said shaft within said 60 casing, a lever carried by said support for raising and lowering said shaft so as to support said container either in or out of contact with the liquid in said casing, a continuously rotating driving element, devices 65 operatively connected to said element for

washing articles in said container while in the lower part of said casing, and means operative upon the movement of said lever for disconnecting said element from said washing device and connecting the same in 70 operating relation to said shaft.

27. In a washing machine, a casing adapted to hold cleansing liquid in its lower part, said casing having a bearing in its bottom wall, a supporting frame beneath said 75 casing, a shaft slidably and rotatably mounted in said bearing, a circular container secured to said shaft within the casing, a lever having one end pivoted to said frame and the other end projecting beneath said shaft, a second lever pivoted to the opposite part of said frame and projecting past said first lever, a tension spring connecting the free ends of said levers, a vertically reciprocable rod connected to the end of said 80 second lever, pounders carried by said rod and projecting over said casing, and means for alternately elevating and releasing said second lever.

28. In a washing machine, a casing 85 adapted to hold cleansing liquid in its lower part, said casing having a bearing in its bottom wall, a supporting frame beneath said casing, a shaft slidably and rotatably mounted in said bearing, a circular container 90 secured to said shaft within the casing, a lever having one end pivoted to said frame and the other end projecting beneath said shaft, a second lever pivoted to the opposite part of said frame and projecting 95 past said first lever, a tension spring connected to said second lever and tending to draw the same downwardly, a vertically reciprocable rod connected to the end of said second lever, pounders carried by said rod 100 and projecting over said casing, and means for raising said first lever.

29. In a washing machine, a casing adapted to hold cleansing liquid in its lower part, said casing having a bearing in its 110 bottom wall, a supporting frame beneath said casing, a shaft slidably and rotatably mounted in said bearing, a circular container secured to said shaft within the casing, a lever having one end pivoted to said frame and the other end projecting beneath said shaft, a second lever pivoted to the opposite part of said frame and projecting past said first lever, a vertically reciprocable rod connected to the end of said second 115 lever, pounders carried by said rod and projecting over said casing, means for alternately elevating and depressing said second lever, and a pedal pivoted to said frame and having an end projecting beneath said first 120 lever.

30. In a washing machine, a casing adapted to hold cleansing liquid in its lower part, said casing having a bearing in its bottom wall, a supporting frame beneath 125

- said casing, a shaft slidably and rotatably mounted in said bearing, a circular container secured to said shaft within the casing, a lever having one end pivoted to said frame and the other end projecting beneath said shaft, a second lever pivoted to the opposite part of said frame and projecting past said first lever, a vertically reciprocable rod connected to the end of said second lever, pounders carried by said rod and projecting over said casing, means for alternately elevating and depressing said second lever, said first lever having a projection extending beneath said second lever and said second lever having its lower edge bent upon an arc substantially concentric with the pivot of said first lever when both of said levers are elevated, and means for elevating said first lever.
31. In a washing machine, a casing adapted to hold cleansing liquid in its lower part, said casing having a bearing in its bottom wall, a supporting frame beneath said casing, a shaft slidably and rotatably mounted in said bearing, a circular container secured to said shaft within the casing, a lever having one end pivoted to said frame and the other end projecting beneath said shaft, a second lever pivoted to the opposite part of said frame and projecting past said first lever, a vertically reciprocable rod connected to the end of said second lever, pounders carried by said rod and projecting over said casing, an arm movable about the pivot of said second lever, means for rocking said arm, and a finger carried by said second lever and adapted to be engaged by said arm upon its upward movement.
32. In a washing machine, a container for fabrics, a frame supporting said container, a lever pivoted to said frame, a vertically reciprocable rod extending upwardly past said container, and connected to the end of said lever, pounders carried by said rod and extending over said container, a spring connected to said lever and tending to depress the same, an arm movable about the pivot of said lever, means for rocking said arm, and a finger carried by said lever and adapted to be engaged by said arm upon its upward movement.
33. In a washing machine, a casing adapted to hold cleansing liquid in its lower part, said casing having a vertical bearing sleeve depending from its bottom wall, a shaft slidably and rotatably mounted in said sleeve, a circular container secured to said shaft inside of the casing, a continuously rotating driving member journaled upon the exterior of said shaft, and having a friction clutch upon its lower surface, a coöperating friction member located beneath said wheel and rotatable with said shaft, a rotatable member geared to said wheel, washing
- mechanism within said casing and operatively connected to said rotatable member, and means for sliding said shaft vertically through said bearing whereby said container is elevated out of the liquid and said friction members are caused to engage each other and said rotatable member is disconnected from said wheel.
34. In a washing machine, a casing adapted to hold cleansing liquid in its lower part, said casing having a vertical bearing sleeve depending from its bottom wall, a shaft slidably and rotatably mounted in said sleeve, a circular container secured to said shaft inside of the casing, a friction wheel journaled concentrically with said shaft and having upon its lower surface one member of a friction clutch, a coöperating friction clutch member located beneath said wheel and rotatable with said shaft, a rotatable member geared to said wheel, a friction disk parallel to said shaft and engaging the edge of said wheel, washing mechanism within said casing and operatively connected to said rotatable member, and means for sliding said shaft vertically through said bearing whereby said container is first elevated out of the liquid and said friction members are next caused to engage each other and said rotatable member is disconnected from said wheel and said wheel is moved past said friction disk so as to increase its speed.
35. In a washing machine, a casing adapted to hold cleansing liquid in its lower part, said casing having a bearing in its bottom wall, a shaft slidably and rotatably mounted in said bearing, a foraminous container secured to said shaft within the casing, a friction wheel rotatably supported coaxially with said shaft, a friction disk supported with its plane parallel to said shaft and operatively engaged with said wheel, means for driving said disk, gearing connecting said wheel and shaft whereby said container is rotated at a speed less than said wheel while in depressed position, means for elevating said shaft relatively to said casing and wheel and simultaneously connecting the same in direct driving relation to said wheel, and means for elevating said wheel after such connection whereby the speed of rotation of said container may be accelerated.
36. In a washing machine, a casing, and a vertically movable container inside said casing, said container having a floating chamber and a perforated portion outside of said chamber.
37. In a washing machine, a casing, a container inside said casing, and means for moving said container to and between different vertical positions therein, said container having a floating chamber.
38. In a washing machine, a casing, and a container inside said casing and movable to and between different vertical positions

therein, said container having an apertured side wall and a double bottom hermetically sealed to form a floating chamber.

39. In a washing machine, a casing adapted to hold cleansing liquid and having a vertical bearing in its bottom wall, a shaft slideable in said bearing, and a tub secured to said shaft inside of said casing, said tub comprising a tube surrounding said shaft, a pair of circular plates secured to the upper and lower ends of said tube respectively and converging together at a distance from their centers, and an upright cylindrical wall formed at the outermost edge of one of said plates.

40. In a washing machine, a casing adapt-

ed to hold liquid in its lower part, an upright cylindrical container supported in said casing above the liquid, means for rotating said container rapidly about a vertical axis, and an anti splashing device beneath said container.

41. In a device of the character described, a tub having a bottom formed of a plurality of concentric oppositely inclined portions, an axial shaft secured to the center of said bottom, and bracing means attached to said shaft and engaging said bottom at a distance from said shaft.

In testimony whereof, I hereunto affix my signature.

JAMES B. KIRBY.
